(57) **CLAIM**

I claim the ornamental design for an adjustable lighting fixture, as shown and described.

DESCRIPTION

FIG. 1 is a top-front perspective view of an adjustable lighting fixture;

FIG. 2 is a top view of the adjustable lighting fixture of FIG. 1;

FIG. 3 is a bottom view of the adjustable lighting fixture of FIG. 1;

FIG. 4 is a first side view of the adjustable lighting fixture of FIG. 1;

FIG. 5 is a second side view of the adjustable lighting fixture of FIG. 1;

FIG. 6 is a third side view of the adjustable lighting fixture of FIG. 1; and,

FIG. 7 is a fourth side view of the adjustable lighting fixture of FIG. 1.

The broken lines in the drawings illustrate portions of the adjustable lighting fixture that form no part of the claimed design.

1 Claim, 7 Drawing Sheets
